UNITED STATES PATENT OFFICE.

JOHN GRAVES, OF BROOKLYN, NEW YORK, ASSIGNOR, BY MESNE ASSIGNMENTS, TO THE NATIONAL WROUGHT STEEL MANUFACTURING COMPANY.

SHEET-METAL SUMMER PIECE AND FRAME.

SPECIFICATION forming part of Letters Patent No. 562,393, dated June 23, 1896.

Application filed November 30, 1894. Serial No. 530,510. (No model.)

To all whom it may concern:

Be it known that I, JOHN GRAVES, a citizen of the United States of America, residing at Brooklyn, in the county of Kings, State of New York, have invented certain new and useful Improvements in Sheet-Metal Summer Pieces and Frames, of which the following is a specification.

My invention relates to improvements in summer pieces and frames for mantels and the method of making the same, particularly to such when made of sheet metal.

Sheet-metal summer pieces and frames are a desirable article of manufacture, being a cheap and light substitute for the heavy and more costly cast-iron summer pieces and frames now generally used, but it has heretofore been impractical to press the frames for reasons which I will now state, referring, for example, to the drawings of my summer-piece, which accompany the specification, and whereof—

Figure 1 is a front elevation of the same; Fig. 2, a vertical section on the line $x-x$ of Fig. 1; Fig. 3, a horizontal section on the line $y-y$ of Fig. 1; Fig. 4, a detail showing the construction by which the cap E is held in place. Fig. 5 is a view of the frame separated from the summer-piece.

Being a sheet-metal worker, I perceived the advantages of sheet-metal summer pieces and frames and made many attempts to press such, but failed because I undertook to press the frame separately from the summer-pieces. By "frames" is meant the corrugated or molded border portion of the article, represented in the drawings which accompany the specification by the part A between the depression I I and the outer margin of the article, the inner part B being the summer-piece. From conditions arising out of the ornamentation and the setting of the mantels, it is necessary that the frame shall extend around only three of the sides of the summer-piece, but not around the fourth side, and in this fact resides the source of the difficulty of pressing the frames. In attempting to press the frames I had taken a sheet of metal, shaped to the general outline of the frame, and attempted to press that in dies having a suitable shape to produce the desired moldings or corruga-

tions, these moldings or corrugations being indispensable in order to give the necessary stiffness to the frame; but all my attempts to press the frame in this manner failed. The cause of the failure was twofold. In the first place, as I was attempting to press the frame alone, and the sheet was therefore shaped as three sides only of a rectangle, and with a large opening in the center where the summer-piece was to be afterward fitted, there was no central metal to resist the effect of the strain resulting from the bending of the frame as the dies closed on it. Consequently, I found that the bending of the metal of the frame, especially at the miters 2 2, 3 3, drew the metal of the sides $a' a'$ of the frame inward, and the result was that the frame came from the die with its sides curved inward, instead of being straight, and this destroyed the frame for all practical purposes. In the second place, there being no metal inside the facings $a a$, the strain of bending the metal at the miters 2 2 cracked the metal across the said facings $a a$, and ruined the frames.

For the causes stated, I for a long time failed in attempting to press a frame; but after much experimenting having determined the causes of failure to be as above explained, I discovered that I could press the metal of the frame into any desired moldings and corrugations, provided I so pressed it in one sheet with the summer-piece, the part forming the summer-piece being cut out of the frame after the frame was pressed.

I discovered that when a sheet of metal large enough to form both the frame and the summer-piece was put into the dies and pressed, the difficulties above mentioned were overcome in the following manner: First, as to the curving in of the sides $a' a'$ of the frame; this was overcome when the frame was pressed in one piece with the summer-piece, because the metal of the summer-piece being held flat between the dies offered so great a resistance to compression or buckling that the sides $a' a'$ of the frame could not curve in, but remained straight; second, as to the cracking of the facing $a a$ at the miters 2 2, the large extent of the metal of the summer-piece being within said miters 2 2, prevented a crack from starting.

In making the frame and summer-piece, I proceed as follows: First, I take a sheet of metal sufficiently large to form both the frame and the summer-piece. Then I put this between dies which have a suitable configuration to produce moldings or corrugations around three sides of the metal near the margin. One of such dies is also fitted with a plunger, the other with a corresponding hole, positioned to produce the opening D for a smoke-pipe from a heater. I also prefer to form across the lower part of the summer-piece the transverse rib b, which serves both to stiffen the summer-piece and to offer additional resistance to the curving in of the frame. Proceeding in this manner, I am able to form the frame without difficulty. The opening D, which can be made in the part that forms the summer-piece, at the same time the frame is pressed, has the raised rim d all around, and a cap E, Fig. 4, is made of sheet metal in suitable manner to fit the opening. The sides e e of said cap being somewhat coned inwardly, as seen, the rim f of the said cap being turned outward to bear on

the rim d, said cap E is held in place by the compression of the sides against the rim d. To facilitate withdrawing the said cap a thumb-hole g is provided in the bottom thereof, as shown.

While Fig. 1 shows the frame before the summer-piece is cut out, Fig. 5 shows the frame after the summer-piece is removed.

To provide for securing the frame in position, eye-pieces h h are riveted on the inside 35 of frame, so that hooks can be carried from them to the wall behind the mantel.

Now, having described my improvement, I claim as my invention—

A sheet-metal fireplace-frame first stamped 40 and then cut from a single and continuous sheet of metal.

In testimony that I claim the foregoing as my invention I have hereunto set my hand this 9th day of June, 1894.

JOHN GRAVES.
